UNITED STATES PATENT OFFICE.

ARTHUR S. THOMPSON, OF ONTARIO, CALIFORNIA.

WATCHMAKER'S DESK OR CABINET.

Application filed March 17, 1926. Serial No. 95,238.

My invention relates to improvements in watchmaker's cabinet or desk, the main object being the provision of a structure which will be compact in size to occupy a small amount of space and which will accommodate all the implements and accessories used by the watchmaker and at the same time provide a perfect work bench and protection for the motor and lathe.

10 Another object of my invention is the provision of a cabinet or desk which will arrange all the implements and accessories in the most convenient places and which while of small and compact size will have 15 a very large holding or accommodating capacity and which will be of ornamental and attractive appearance.

Another object of my invention is a provision of a cabinet or desk which will be of 20 simple, strong and durable construction, which can be produced at the right price all things considered and which in every particular will be desirable and practical for the purposes intended.

25 With these objects in view my invention consists of a desk or cabinet embodying novel features of construction and arrangement of parts for service, substantially as described and defined by the claim, and as 30 shown in the accompanying drawings, in which:

Figure 1 represents a perspective view of the complete desk or cabinet constructed in accordance with my invention.

35 Figures 2 and 3 represent perspective views of the novel construction of drawer which embodies the sliding assembling pan and the cup slide for benzine and wood alcohol.

40 Figure 4 represents a perspective view of the sliding filing block and its associated mechanism.

Figure 5 represents a detail view of the 45 drawer for balance staffs, jewels and bottle rack.

Figure 6 represents a detail view of the drawer for graver tools, and

Figure 7 represents a perspective view of the 50 drawer which contains the tool compartment, and file and staking devices.

Referring by numeral to the drawings in which the same numerals of reference are used to designate the same parts in all the figures:

55 The numeral 1 designates the top forming

the bench of my cabinet, which is of rectangular shape and of the desired size and is provided with a suitable rim or flange 2, which is open at the front and upon the rear portion of the bench is mounted the case 3, which is provided with glass enclosures 4, in the form of sliding doors, and this enclosure provides the motor case and has openings 5, to allow the passage of the belt to the lathe, which is not shown. 60

The desk is provided with the front board 6, in which is mounted the drawer 7 for the reception of materials and the drawer 7', for receiving the balance staffs, jewels and providing a bottle rack, said drawer being 70 shown in Figure 5 and having a wall 8 provided with receiving openings 8'.

Between the drawers 7 and 7' is located a plate 9, formed with an opening 9', in which is mounted the filing block 10, said 75 filing block moving in guides 11, extending from the front board 6, and is provided with a cross strip 12, to which at one end is connected the chain 13, which passes out through the opening 14 and is provided 80 with a ring 15, the purpose of which is to slide the block out when desired, the block in normal position being pushed back in the guide and out of the way.

The desk is provided with the end walls 85 16, and the intermediate walls 17, which are spaced apart to form the chamber or recess 18, which receives the legs and feet of the watchmaker when at work, and in the spaces thus formed at each side is 90 mounted the pair of sliding drawers 19, which are designed as chuck drawers, the series of three drawers 20, which are designed to receive crystals, and the two lower drawers 21 for work and envelope reception 95 and the drawer 22 for receiving main and clock springs.

On the opposite side of the desk in the space provided is the upper drawer 23 which is to receive graving tools and is provided 100 with a suitable rack 24 and below this drawer is the drawer 25 which is adapted to serve as a tool compartment, having a receptacle portion 26 and a tool receiving plate 26', while below said latter drawer are the series 105 of additional drawers 27.

In the space at the top is mounted a drawer 28 which is desirable for the reception of the worker's apron and below this drawer is the open or frame shaped drawer 110

29, which has mounted in the outer portion thereof the plate 30 having cups 31 to receive benzine and wood alcohol, which cups are protected by the sliding cover 32, guided in the ways 33, of said open frame shaped drawer.

It will be noted from the drawings taken in connection with the description that I provide a desk or cabinet which receives the 10 materials, tools and accessories used by the watchmaker and arranges them in the most desirable and convenient position to permit ready access and use and that I provide a desk or cabinet which will recommend itself 15 as meeting every requirement of the watchmaker for a practical, useful and desirable structure of this character.

I claim:

A drawer for use in a watchmaker's cabinet, comprising a rectangular frame, the 20 said frame being provided with transverse and longitudinal guides, a plate provided with depressed cups mounted in said transverse guides, the said plate being of less width than the internal width of said frame, an apron tray of less length than the 25 internal length of said frame and mounted in said longitudinal guide above said plate, whereby the said tray may be slid over said plate.

In testimony whereof I hereunto affix my signature.

ARTHUR S. THOMPSON.
